UNITED STATES PATENT OFFICE.

GEORGE DE LAVAL, OF CAMBRIDGE, AND GEORGE P. ABORN, OF BOSTON, MASSACHUSETTS, ASSIGNORS TO THE GEO. F. BLAKE MFG. CO., OF NEW YORK, N. Y., A CORPORATION OF NEW JERSEY.

AIR-COMPRESSOR.

SPECIFICATION forming part of Letters Patent No. 738,920, dated September 15, 1903.

Application filed July 25, 1901. Serial No. 69,639. (No model.)

To all whom it may concern:

Be it known that we, GEORGE DE LAVAL, residing in Cambridge, Middlesex county, and

5 GEORGE P. ABORN, residing in Boston, Suffolk county, Massachusetts, citizens of the United States, have invented certain new and useful Improvements in Air-Compressors, of which the following is a specification.

Our invention relates to air-compressors; 10 and it has for its object to lessen the amount of air compressed and furnished to the receiver should the pressure in the receiver reach above normal. This is accomplished by retarding the closing of the inlet-valve to 15 lessen the effective stroke of the piston, thereby only compressing an amount of air sufficient for use.

We will describe an air-compressor embodying our invention and then point out the 20 novel features thereof in the claims.

In the accompanying drawings, Figure 1 is a side elevation of an air-compressor embodying our invention and of an engine for operating the compressor. Fig. 2 is a detail sec-

25 tional view of a portion of the compressor. Fig. 3 is a detail view of the valve-gear mechanism, the parts thereof being at the position they assume under normal action when the piston of the compressor is at left-hand end of

30 cylinder. Fig. 4 is a detail view of the valve-gear mechanism, the parts thereof being in the position they assume under normal pressure when the piston of the compressor is at mid-stroke going toward the right. Fig. 5 is a de-

35 tail view of the valve-gear mechanism, the parts thereof being in the position they assume under normal action when the piston of the compressor is at mid-stroke moving toward the left. (See Fig. 2.) Fig. 6 is a detail

40 view of the valve-gear mechanism, the parts thereof being in the position they assume under excessive pressure, the piston being at the left-hand end of stroke. Fig. 7 is a view in elevation of the air-compressor and showing

45 a means for operating the valve-gear mechanism, said means being put into operation by excessive pressure in the receiver. Figs. 2 to 7, inclusive, are drawn to a larger scale than Fig. 1. Fig. 8 is a detail view of a part of a 50 fluid regulator comprised as my invention.

Fig. 9 is an enlarged detail, partly in section, showing the water-valve of the regulator.

Similar characters of reference designate corresponding parts in all the figures.

A represents the cylinder of the air-com- 55 pressor; B, an engine, here shown as consisting of a Corliss steam-cylinder, for operating the piston; A', the air-compressor, and b an eccentric on the driving-shaft b', operated by the engine B.

B' represents a governor for operating the trips of the engine.

At each end of the compressor we provide a valve a, which is operated to permit air from the atmosphere to enter the cylinder 65 and to permit compressed air from within the cylinder to pass to the compressed-air receiver. a' represents the passage for air to within the cylinder, and a² the passage for compressed air out of the cylinder to the receiver. Puppet-valves a³ are provided in this passage at each end of the cylinder, which valves prevent compressed air from the receiver returning to the cylinder A. Each valve a is provided with an operating valve- 70 stem a⁴, and each stem is provided with the following mechanism, which when operated causes the valve to shift or change its position.

The mechanism provided for each valve- 80 stem preferably comprises an arm a⁴, which is fixed to the valve-stem, an arm a⁵, which is loose on the valve-stem, a worm-segment a⁶, carrying a cam-segment a⁷, also loose on the valve-stem, a bell-crank lever a⁸, fulcrumed on the arm a⁵, and a link a⁹, which connects one end of the bell-crank lever with the arm a⁴. The other end of the bell-crank lever is provided with a roller a¹⁰ or other similar device, which rides on the periphery 85 of the cam-segment a⁷, it being held thereagainst by a spring a¹¹. The arm a⁵ is rocked by means of a rod or link a¹², connecting it with a wrist-plate C, which is rocked or oscillated from the eccentric b.

Referring now more particularly to Fig. 3, the parts of the valve-gear are here shown in the position which they assume when the compressor is being operated and the pressure is not above normal. In this figure it will be

seen that the pivots or points of connection 1 2 3 of the parts a^4 , a^8 , and a^9 are in alinement. Consequently when the arm a^5 is rocked the arm a^4 will be rocked an equivalent distance. The parts a^4 , a^8 , and a^9 constitute a toggle, and to have the toggle fully effective the pivots 1 2 3 have to be in alinement. This alinement is maintained by means of the roller a^{10} , traveling on the peripheral edge 10 a^{13} of the cam-segment a^7 . This edge is necessarily concentric with the valve-stem a^8 . Figs. 3, 4, and 5 show the parts in position for normal pressure, and in these positions the valve is closed first to the atmosphere, 15 next open to the atmosphere, and then opened to the receiver. Should pressure in the receiver reach above normal, the excess pressure will act to retard the time of closing of the valve, and thus force all air drawn in the 20 cylinder out again to the atmosphere. This is accomplished in the present instance by moving the cam-segment so that during one portion of the movement the roller a^{10} is not in engagement with the concentric portion 25 thereof, and consequently the toggle formed by the arm a^4 , link a^9 , and bell-crank lever a^8 will be broken and (see Fig. 6) the movement of the arm a^4 consequently shortened.

The shifting of the cam-segment is preferably operated through a medium of water and air pressure, and this may be accomplished by the following arrangement of parts, (see Fig. 7:)

E represents a cylinder provided with a dia- 35 phragm and a part connected therewith which when air is admitted under the diaphragm causes the outer end of a fulcrumed lever e to be raised or lifted.

e' represents the air-inlet to the cylinder, 40 which inlet is in communication with the compressed-air receiver. (Not shown.) The lever e , which is provided with adjustable weights, actuates a rod e^2 , which rod moves a valve e^{17} in the cylinder e^3 through its stem e^{18} . The cylinder e^3 receives water under pressure through a conduit e^4 and discharges it through a conduit e^5 to a cylinder e^6 , having a piston e^7 . When the valve in the cylinder e^3 is moved upward, water enters the 50 cylinder e^6 and moves the piston e^7 upward. The piston e^7 is provided with a pulley e^8 , over which a chain e^9 passes. One end of the chain is secured to a stationary support—as, for example, the cylinder e^6 —and its other end is 55 provided with a weight e^{10} . Intermediate its ends it passes over and operates a sprocket e^{11} , which is fast on a shaft e^{12} . The shaft e^{12} is provided with a pair of worm-screws e^{13} , one for each worm-segment, so that when the 60 shaft is rotated the cam-segments a^7 will be moved. At the time that the piston e^7 is moved upward a lever e^{15} is moved on its fulcrum with it, the connection between the two being a cord e^{14} , and this lever through a cam 65 e^{80} , carried thereby, moves the pipe e^5 and cylinder e^3 relatively to the valve e^{17} therein, which is then held stationary by the lever e ,

thereby closing the water-inlet and suspending the piston e^7 in a definite position. By having water instead of compressed air actuate the piston e^7 and locking the water under the piston by the action of said piston in rising, when it raises the lever e^{15} and by the cam carried upon the end thereof jacks up the cylinder e^3 sufficiently to move it and the valve-seats therein relatively to the valve e^{17} , which is at the time held stationary by the lever e , so as to close the passage-ways within the cylinder e^3 , the position of the valves a through the intervening parts are held in 80 their adjusted positions. When excessive pressure in the receiver falls, the lever e drops and carries with it the rod e^2 , which draws down the valve within the cylinder e^3 and opens ports to permit water under the piston 85 e^7 to drain off through the pipe e^{16} . As the water escapes the piston e^7 drops and returns the cam-segments back to the position shown in Figs. 3, 4, and 5 to permit the compressor to act normally. This action also permits the lever e^{15} and cylinder e^3 to resume their 90 lowest normal positions with the water-inlet e^4 closed.

The valve e^{17} in Fig. 9 is shown in the position indicated in Fig. 7, in which the cylinder e^3 has been raised by the action of the cam on the lever e^{15} , so as to close the passage-ways within the cylinder. These conditions continue until the lever e drops, carrying with it the valve-stem e^{18} and valve e^{17} and opening the waste through the valve-seat e^{19} and cut-away portion e^{20} of the valve. e^{21} indicates a full-sized portion of the valve e^{17} , which alternately closes the passage-ways through the valve-seats e^{19} e^{22} , and when the cylinder is raised by the cam it closes both of them. When the lever e drops, the valve e^{17} is moved down to its lowest position, when the part e^{21} is fully housed within the valve-seat e^{22} , the reduced portion e^{20} being then 110 within the opening of the valve-seat e^{19} , thereby permitting the water to escape from the pipe e^5 through the outlet e^{23} . The valve e^{17} is provided with a second reduced portion e^{24} , which when in its highest position when it has been raised by the lever e permits the 115 water to flow through the inlet, up through the valve-seat e^{22} , and to the cylinder e^6 through pipe e^5 .

What we claim as our invention, and desire to secure by Letters Patent, is—

1. In an air-compressor having a cylinder, a piston, inlet-valves, the combination of a mechanism comprising a toggle for operating said valves, and a device open to the excess pressure in the receiver or reservoir for breaking the said toggle whereby the closing of said valves is retarded and a lesser amount of air than usual compressed.

2. In an air-compressor having a cylinder, a piston and inlet-valves, the combination of a mechanism comprising a toggle for operating said valves, and a device open to the excess pressure in the reservoir or receiver for

breaking said toggle whereby the closing of said valves is retarded and lesser amount of air than usual compressed, said device comprising a diaphragm which is affected by said excess pressure, and a piston operated by water-pressure, the valve for which is controlled by said diaphragm and the said valve.

3. In an air-compressor having a cylinder, a piston and inlet-valves, the combination of 10 mechanism comprising a collapsible part for operating said valves, which mechanism under normal pressure throws the valves to completely open and close the passages which they control, and a mechanism open to excess 15 pressure from said cylinder for affecting said collapsible part whereby the effective throw of the said mechanism is lessened and the closing of said valves is retarded.
4. In an air-compressor having a cylinder, 20 a piston and inlet-valves, the combination of a mechanism comprising a toggle for throwing said valves to open and close the passages they are located in, and a device for breaking said toggle whereby the effective throw 25 of the said mechanism is lessened.

5. In an air-compressor having a cylinder, piston and inlet-valves, the combination of a mechanism for throwing each of said valves, each mechanism comprising a movable cam- 30 segment, an arm fixed to the valve, a bell-crank lever carried by a swinging support and adapted to have an arm travel over the cam-

surface of the segment, and a link connection between the other arm of the bell-crank lever and the arm fixed to the valve, and 35 means affected by excess pressure in the reservoir or receiver for shifting the position of said cam-segment whereby the toggle formed by the said bell-crank lever, link and arm is broken and the throw of the valve thereby 40 affected.

6. In an air-compressor having a cylinder, piston and inlet-valves, the combination of a mechanism for throwing each of said valves, each mechanism comprising a movable cam- 45 segment, an arm fixed to the valve, a bell-crank lever carried by a swinging support and adapted to have an arm travel the cam-surface of the segment, and a link connection between the other arm of the bell-crank lever 50 and the arm fixed to the valve, a shaft geared to said cam-segments, and means for rotating said shaft to shift the position of the cam-segments, which means are put in operation by excess pressure in the reservoir or receiver. 55

In testimony whereof we have signed our names to this specification in the presence of two subscribing witnesses.
